(57) **CLAIM**

The ornamental design for a cabinet lamp, as shown and described.

DESCRIPTION

FIG. 1 is a front and top perspective view of a cabinet lamp, showing our new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a rear elevational view thereof; and,

FIG. 7 is a bottom plan view thereof.

The broken lines depict portions of the cabinet lamp that form no part of the claimed design.
